Primary Examiner — Robin V Webster*(74) Attorney, Agent, or Firm* — Ohlandt, Greeley, Ruggiero & Perle, LLP; Edward I. McMahon(57) **CLAIM**

The ornamental design for the blind duster, as shown and described.

DESCRIPTION

FIG. 1 is a perspective view of a blind duster according to the present disclosure;

FIG. 2 is a front elevation view of the blind duster of FIG. 1;

FIG. 3 is a rear elevation view of the blind duster of FIG. 1;

FIG. 4 is a left side elevation view of the blind duster of FIG. 1;

FIG. 5 is a right side elevation view of the blind duster of FIG. 1;

FIG. 6 is a top plan view of the blind duster of FIG. 1; and,

FIG. 7 is a bottom plan view of the blind duster of FIG. 1.

The broken lines in the drawings illustrating environmental structure or boundaries that form no part of the claimed design.
